UNITED STATES PATENT OFFICE.

GEORGE OTSTOT, OF SPRINGFIELD, OHIO.

DESIGN FOR A TOY.

46,540.

Specification for Design. Patented Oct. 13, 1914.

Application filed August 8, 1914. Serial No. 855,912. Term of patent 7 years.

To all whom it may concern:

Be it known that I, GEORGE OTSTOT, a citizen of the United States, residing at Springfield, in the county of Clark and State of Ohio, have invented a new, original, and ornamental Design for a Toy, of which the following is a specification, reference being had to the accompanying drawing, forming a part thereof.

The figure is a front view, partly in perspective, showing my new design.

I claim:

The ornamental design for a toy, as shown.

GEORGE OTSTOT.

Witnesses:

CHAS. I. WELCH,
EFFA M. SMITH.
